UNITED STATES PATENT OFFICE.

TALBOT LENNOX, OF CHICAGO, ILLINOIS, ASSIGNOR TO MCGUIRE-CUMMINGS MANUFACTURING COMPANY, OF CHICAGO, ILLINOIS, A CORPORATION OF ILLINOIS.

CAR-DOOR HOOK.

No. 874,689.

Specification of Letters Patent.

Patented Dec. 24, 1907.

Application filed December 31, 1904. Serial No. 238,156.

To all whom it may concern:

Be it known that I, TALBOT LENNOX, a citizen of the United States, residing at Chicago, in the county of Cook and State of Illinois, have invented certain new and useful Improvements in Car-Door Hooks, of which the following is a specification, reference being had to the accompanying drawings.

10 My invention relates to hooks for grain-car doors, and has for its object to provide a new and improved hook capable of performing all the functions of the hook at present in use, but which will also be adapted to 15 swing longitudinally of the car. Such hooks as at present constructed are not capable of swinging longitudinally, and as they hang down a considerable distance from the roof of the car, they are apt to be damaged when 20 the car is loaded with lumber, or freight other than grain.

I accomplish my object as illustrated in the drawings and as hereinafter described.

What I regard as new is set forth in the 25 claims.

In the accompanying drawings,—Figure 1 is a partial cross-sectional view of a grain-car; Fig. 2 is a perspective view of my improved hook; Fig. 3 is a perspective view of 30 the lower portion of the hook; and Fig. 4 is a vertical section on line 4—4 of Fig. 1.

Referring to the drawings,—5 indicates one of the roof-timbers; 6 one of the door-posts; 7, the car-door; and 8, one of the supports or guides with which the upper edge of 35 the door is connected and along which it moves when raised to its inoperative or horizontal position. Preferably, such guide is of the construction shown in my application of even date herewith, but it may be of 40 any other approved construction.

9 indicates the hook, which, as shown, comprises a U-shaped member, 10 adapted to be pivoted to the roof-timber 5 or other 45 suitable support, as shown in Fig. 4,—in which 11 indicates the pivot of said member. The member 10 has lugs 12 at the side next to the car-door, which are arranged to be struck by the edge of the door when it is 50 raised to its horizontal position,—thereby throwing the lower or retaining member of

the hook under the lower edge of the door. Said member 10 is provided with a seat in its lower or horizontal portion 13, which seat is adapted to receive the pivot-rod 14 of the 55 retaining-member 15 of the hook. Said retaining-member is best shown in Fig. 3,—from which it will be seen that it has an upwardly-projecting finger or hook 16, and also lugs 17 in which the pivot-rod is secured. 60 By arranging the pivot-rod as shown, the retaining-member may be slipped over one of the wings of the upper member and fitted in its seat, as shown in Fig. 2. To retain the pivot-rod 14 in place, lugs 18 are provided at opposite sides of its seat, which are adapted to be folded over said pivot-rod in the manner shown in Fig. 4.

By the construction described, it will be observed that the hook as a whole may 70 swing toward and from the door in the usual way,—both members of the hook swinging as a unit, since the retaining-member is free to swing upon an axis which is perpendicular to the axis of the hook as a whole. Said 75 retaining-member may, however, be swung longitudinally of the car, and consequently is not apt to be injured if accidentally struck.

So far as I am aware, no one has heretofore provided a car-door hook having this 80 double pivotal movement, and therefore my invention is not limited to the specific construction illustrated, except in so far as it is particularly claimed, but includes, generically, the subject-matter of the broader 85 claims.

What I claim as my invention and desire to secure by Letters Patent is,—

1. The combination with a car, of a car-door hook having an upper member pivotally connected with the upper portion of the car, and having an arm projecting toward the car door, and a lower retaining member pivotally connected with said upper member and arranged to swing in a plane lying 95 at an angle with the plane of movement of the upper member.

2. The combination with a car, of a hook comprising an upper member pivotally mounted in the upper portion of the car to 100 swing toward and from the car door, and having an arm projecting toward the car

door, and a lower retaining member pivotally connected with the upper member so as to swing longitudinally of the car.

3. A car-door hook, comprising an upper member arranged to swing toward and from the car door and having an arm projecting toward the door, and a lower member pivotally connected with said upper member

so as to swing only longitudinally of the car, said lower member having a retaining hook adapted to engage the door.

TALBOT LENNOX.
